UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

ASH HOPPER.

1,422,900.

Specification of Letters Patent. Patented July 18, 1922.

Application filed October 6, 1921. Serial No. 505,703.

To all whom it may concern:

Be it known that I, ARTHUR P. STRONG, a citizen of the United States, residing at Chicago, in the county of Cook and State of Illinois, have invented new and useful Improvements in Ash Hoppers, of which the following is a specification.

This invention relates to metal hoppers or tanks for the collection and disposal of ash 10 or other disintegrated materials.

One object of my invention is to make the walls of the tank or hopper of supporting beams and metal plates and to secure the plates to the beams by bolts in such a manner that one bolt is common to two plates.

A further object of the invention is to cover the heads at the inner end of the bolts by overlapping the plates at the bolts and provide the overlapped portion of the plates 20 with registering recesses to receive the bolt heads and thus protect the same from corrosion or abrasion from the material packed against the plates.

The invention consists further in the matters hereinafter described and more particularly pointed out in the appended claims.

In the accompanying drawings—

Fig. 1 is a side elevational view of a storage tank or hopper constructed in accordance with my invention;

Fig. 2 is an enlarged fragmentary inside view of a portion of one of the upright walls of the tank or hopper;

Fig. 3 is a horizontal sectional view taken 35 on line 3—3 of Fig. 2;

Fig. 4 is a vertical sectional view taken on line 4—4 of Fig. 2; and

Fig. 5 is a perspective view of one of the wall plates.

In the drawings, I have shown a storage tank or hopper of the type having upright side walls 1, 1, and a hopper bottom 2 provided with a gate controlled discharge opening, as customary in structures of this general kind. The tank or hopper is usually elevated or supported above the ground or platform, as the case may be, a distance sufficient to permit emptying of the hopper or tank into a car or truck when moved under the same. As shown in Fig. 1, the structure includes upright supporting posts 3, 3 for elevating the tank. The upright side and end walls 1, 1 rest on and are connected with a horizontal base frame 4 at the upper 55 ends of the posts 3, as indicated in Fig. 1.

The side and end walls 1 are made alike, so a description of one will suffice for all.

Secured to the base frame 4 are a plurality of upright beams or members 5, 5. These are laterally spaced apart and, as shown in Fig. 3, are preferably in the shape of I-beams. Said beams 5 extend upward the same distance and are connected together at their upper ends by a cross-member 6 at the top of the tank or hopper, as shown in Fig. 1.

The spaces between the upright beams 5, 5 are closed by vertical rows of metal plates 7, 7. The plates in each row are arranged one above the other and are located inside of the beams 5, as shown. The plates 7 are secured to the beams between which they extend by bolts 8, 8, these being at the upper edge of each plate only, in the form of structure shown in the drawings. The bolts 8 extend through the plates and the side flanges of the beams 5 overlapped by the plates and have their heads inside of said plates, while their outer threaded ends project outside of the beams and in position to have clamp nuts applied thereon.

As shown in Fig. 4, the upper edge or margin of a plate 7 in each vertical row is overlapped on the inside by the lower margin of the plate 7 thereabove in the same row. This provides a downward shed and makes leak-proof joints between such margins of the plates. The overlapping portions of the plates 7, 7 have registering recesses 10, 11 to receive and accommodate the bolt heads 9. This permits one plate to overlap the other in substantially close contact, and thus insures a proper joint between the two, and further protects and shields the bolt heads from contact with the material packed in the tank. As a result, the bolt heads 9 are protected from corrosion or abrasion from such material. This is a decided advantage in ash hoppers, not only because of the marked abrasive property of such material, but because it is discharged into the hopper damp and hot, and corrosion of the bolts would follow if exposed to contact with such material. Moreover, the bolt heads are not allowed to project into the hopper and thus do not form shoulders or ledges for the material to accumulate and collect on.

The plates 7 in each horizontal row overlap along their side edges or margins and

throughout the full length of the same. This overlapping is also along the associated beams 5, and one bolt 8 is inserted through two plates. There are two bolts for each 5 plate, one at each of the upper corners thereof, and with each bolt common to each two plates. This reduces the number of bolts required in the structure and thus saves labor and expense in making and erecting 10 the same. As shown in Figs. 2 and 5, the plates 7 are flat and substantially rectangular in shape with their side edges parallel but inclined. This causes the lower left-hand corner of each plate in one vertical row to be 15 over the upper right-hand corner of the plate therebelow and immediately to the left, when the structure is viewed as in Fig. 2. Moreover, the plates overlap at the corners, as shown in Fig. 3.

20 While I have shown and described herein in detail a storage tank or hopper constructed in accordance with my invention, it is of course to be understood that the details of construction and arrangement of parts may 25 be variously changed and modified without departing from the spirit and scope of my invention.

I claim as my invention:

1. A tank wall, comprising plate supporting beams, plates arranged inside of said beams and closing the spaces between the same, and bolts securing the plates to said beams, the heads of the bolts being inside and overlapped and covered by the marginal 35 portions of adjacent plates for protecting the bolts from contact with the material packed against the inside of said wall, said

plates having recesses to receive and accommodate the bolt heads.

2. A tank wall, comprising upright beams 40 laterally spaced apart, a row of vertically arranged plates in each of the spaces between the beams and extending between the same, said plates having their side margins at the beams and overlapping the side margins of 45 adjacent plates, and bolts securing the plates to said beams and extending through the overlapped side portions thereof, the lower ends of the plates in each vertical row overlapping on the inside the upper ends of the 50 plates therebelow in said row and covering the inner ends of the bolts.

3. A tank wall, comprising upright beams laterally spaced apart, a row of vertically arranged plates in each of the spaces between 55 the beams and extending between the same, said plates having their side margins at the beams and overlapping the side margins of adjacent plates, bolts securing the plates to said beams and extending through the overlapped side portions thereof, the lower ends 60 of the plates in each vertical row overlapping on the inside the upper ends of the plates therebelow in said row and covering the inner ends of the bolts, and said plates 65 having inclined side edges so that one lower corner of each plate overlaps an upper corner and bolt thereof of a plate in the adjacent row.

In testimony that I claim the foregoing as 70 my invention, I affix my signature, this 29th day of September, A. D. 1921.

ARTHUR P. STRONG.
